X-RAY MACHINE MOVING DEVICE

Martin A. Mikesh, Lawrenceville, N. J., assignor
to The M. W. Kellogg Company, New York,
N. Y., a corporation of Delaware

Application August 28, 1941, Serial No. 408,603

1 Claim. (Cl. 280—3)

This invention relates to a moving device for simply and accurately positioning a wheeled X-ray machine relative to the object to be tested.

In the X-ray testing of large metallic objects, such as the welded seams of plate, vessels, nozzles, and piping of the heavy construction industries, it is necessary to have comparably large supports for both the workpiece and the X-ray machine. Movement devices are usually provided for both the workpiece and the X-ray machine. It is with the latter that this invention is particularly concerned.

It is common present practice to mount the X-ray apparatus on a large wheeled vehicle having devices for steering the same, but not provided with a source of power for self-propulsion. In view of the relatively small amount of movement required after the apparatus has been wheeled to its general position for use, it has not been found practical from a cost standpoint to provide means for motive power. It has therefore been the practice to make the necessary changes in position by hand-pushing. Because of the extreme size and weight of the apparatus this has often required the efforts of several workmen. It will readily be appreciated that very exact positioning, or very slight movement of the apparatus, is extremely difficult under these conditions, many forward and reverse movements often being required for a single accurate positioning.

It is therefore a principal object of this invention to devise a driving apparatus for providing vernier-like movement of a wheeled X-ray machine, of practical and simple construction, combined with sturdiness for its intended use and low cost of manufacture.

A further object is to provide an efficient hand-operated driving device to be supported by an X-ray carriage frame and engageable with a wheel of the carriage to move the latter with vernier-like control in either direction.

Other objects will be apparent from a consideration of the following specification and claim taken in connection with the accompanying drawing forming a part of this application, in which:

Fig. 1 is a view in elevation of a wheeled X-ray machine in operating position under a diagrammatically illustrated workpiece;

Fig. 2 is an enlarged view of the driving mechanism, in elevation; and

Fig. 3 is a side view of Fig. 2.

Referring to the drawing, Fig. 1 shows an

X-ray mechanism 5 mounted on a frame 6 supported for movement by front and rear sets of wheels 7. A steering mechanism is provided for the rear set of wheels at 8.

5 The wheel moving device, generally indicated at 9, and clearly shown in Figs. 2 and 3, is pivotally mounted on the end of a shaft 10 attached to and extending from the side of frame 6.

Device 9 includes a housing having spaced, 10 vertical, angle-iron members 11 connected across their upper and lower ends by plates 12 and 13 respectively. Short pieces of angle-iron 14 are attached to the lower ends of vertical members 11. Aligned holes are provided in the pieces 14 to 15 freely receive the shaft 10. Collars 15 on shaft 10 prevent endwise movement of the housing on the shaft.

A hand-crank 16 is mounted on one end of a 20 driving shaft 17 supported for rotation in journal blocks 18 attached on top of plate 12. A pinion 19 secured on the opposite end of driving shaft 17 engages a gear 20 secured to one end of a driven shaft 21 supported for rotation in journal blocks 22 attached to the sides of vertical angle-iron members 11. A friction-wheel 23 is securely mounted on shaft 21 between the upright members 11. Friction-wheel 23 engages the surface of a wheel 7. Wheel 23 is composed of, or at least surfaced with, a substance which 25 will have a high coefficient of friction with the surface of wheel 7. For example, I have obtained satisfactory results by using pneumatic rubber tires for the wheels of the X-ray carriage and forming the friction-wheel 23 of wood.

30 The housing of device 9 is rotated about shaft 10 to bring the wheel 23 into, and release it from, driving engagement with the wheel 7 of the carriage. For this purpose a compression device is provided. A lug 24 centrally secured to the under side of plate 12 pivotally supports an internally threaded member 25. A screw 26 having a hand-knob 27 at one end is supported 35 for free rotation in a side of an angle iron member 28 secured to, and extending from the side of, frame 6. Screw 26 cooperates with threaded member 25 to move friction-wheel 23 toward or away from wheel 7. The pressure of wheel 23 against wheel 7 necessary to avoid excessive slippage is provided through this compression device.

40 From the foregoing it is obvious that I have provided a simple and efficient means for slowly and accurately driving a heavy portable X-ray

55 machine.

I claim:

In combination with a portable X-ray machine having a frame and wheels supporting the same, a housing pivotally attached at its lower end to one side of said frame adjacent one of said wheels, an internally threaded member pivotally attached to the upper end of said housing, a feed-screw supported from said frame and adapted to rotate freely in its support, said feed-screw co-operating with said internally threaded member

10

to rotate said housing toward and away from said wheel, a crank-operated drying shaft and a driven shaft journaled in said housing, a gear train connecting said shafts, and a friction-wheel secured to said driven shaft, said friction-wheel being movable into and out of operating engagement with the periphery of said wheel by means of said feed-screw.

MARTIN A. MIKESH.
